UNITED STATES PATENT OFFICE.

FRANKLIN W. KREMER, OF WADSWORTH, ASSIGNOR OF ONE-HALF TO
CHARLES O. BARTLETT, OF CLEVELAND, OHIO.

FENCE-MACHINE.

SPECIFICATION forming part of Letters Patent No. 436,004, dated September 9, 1890.

Application filed April 8, 1890. Serial No. 347,126. (No model.)

To all whom it may concern:

Be it known that I, FRANKLIN W. KREMER, a citizen of the United States of America, residing at Wadsworth, in the county of Medina and State of Ohio, have invented certain new and useful Improvements in Fence-Machines, of which the following is a specification, reference being had therein to the accompanying drawings.

10 My invention pertains to an improvement in fence-machines; and it consists in the novel construction, combination, and arrangement of parts, as hereinafter more fully shown and described, whereby the machine may be readily operated by one person in twisting the wire and weaving the fence, as will more fully appear from the following description and accompanying illustration, in which—

20 Figure 1 is a side elevation of a portion of a fence, showing the twister, the tension device, and the gage-post in position in building a fence. Fig. 2 is a side elevation of the tension device. Fig. 3 is a horizontal section thereof. Fig. 4 is a side elevation of one of 25 the holders on the gage-post, the post being broken away. Fig. 5 is a front elevation of the same. Fig. 6 is a side elevation of the twister and spacing device combined, and Fig. 7 is a plan view thereof.

30 In the embodiment of my invention, in the construction of the tension device I employ a frame A, open at its rear end, and connected to the post A' by a screw through the flange A².

35 Pivoted at a⁵ in one end of the frame A is an approximately L-shaped cover or clamp a, arranged to be tightened by means of a thumb-screw a' on the screw a², having its head countersunk in a recess a³ and projected 40 through a partition a⁴ in the center of the frame A, cast integral therewith.

In the front side of the frame A are recesses b b, through which the fence-wires b' b' are inserted and drawn. In stretching the wire 45 the cover or clamp a is raised in a vertical position, and the wire is then inserted in the recesses b b and over the top of the partition

a⁴ and stretched by a suitable device. (Not shown.) The L-shaped clamp is then secured in place by the thumb-screw a', thus holding 50 the wire securely in tension. The holders C on the gage-post C' are formed in a single piece and are cast approximately U-shaped, the parallel arms c c being used to secure the holders C to the gage-post C' by means of 55 screws through said arms. Projected from the upper corners of the cross or connecting piece c' are curved arms c² c², forming a space between the inner edges of said arms and the outer edges of the post, through which the 60 wires b' b' are projected.

In the construction of the combined twister and spacing device I employ a frame D, in the upper end of which is designed to slide backward and forward a toothed bar d, having on one end a handle d'. This bar gears with a pinion d², pivoted in the frame D, and having a slot d³ therein for the reception of the wires b' b'. Thus it will be seen that when the bar d' is moved backward and forward the slotted wheel or pinion d² is caused to revolve, thus twisting the wires.

E E are arms approximately L-shaped, their longer ends being adjustably secured in a recess e in the top of the frame D by means of 75 a screw e', and thus by extending these arms the space between the pickets is increased. These arms E E are adjusted on either side of the frame the proper distance. The palings are then adjusted against the arms and the 80 wire twisted, thus forming a fence wherein the palings are equally spaced apart. Thus constructed a very efficient and complete fence-machine is produced.

Having thus fully described my invention, 85 what I claim, and desire to secure by Letters Patent, is—

1. In a fence-machine, the spacer comprising the adjustable arms projected on either side of their holder and having a handle 90 thereon, substantially as shown and described.

2. In a fence-machine, the spacer consisting of the adjustable arms, approximately L-shaped, having their inner ends projected

through a slot in their holder and adjustable by means of a set-screw, substantially as shown and described.

3. In a fence-machine, the spacer consisting of the frame having a recess in its upper end, in which are inserted the longer ends of the L-shaped spacing-arms and secured therein by means of a screw, substantially as shown and described.

4. In a fence-machine, the spacer having 10 the adjustable arms projected on either side thereof, substantially as shown and described.

In testimony whereof I affix my signature in presence of two witnesses.

FRANKLIN W. KREMER.
